CLAIM

I claim the ornamental design for a headband, as shown and described.

DESCRIPTION

FIG. 1. is a perspective view showing my new design in use. The broken line showing the human form is for illustrative purposes only and forms no part of the claim design;

FIG. 2 is a perspective view thereof;

FIG. 3 is a bottom plan view thereof;

FIG. 4 is a top plan view thereof;

FIG. 5 is a right side elevation view thereof.

FIG. 6 is a left side elevation view thereof;

FIG. 7 is a front elevation view thereof; and,

FIG. 8 is a back elevation view thereof.

1 Claim, 6 Drawing Sheets
